METHOD OF SHELL CONSTRUCTION

Application filed March 26, 1931. Serial No. 525,563.

(GRANTED UNDER THE ACT OF MARCH 3, 1883, AS AMENDED APRIL 30, 1928; 370 O. G. 757)

This invention described herein may be manufactured and used by or for the Government for Government purposes, without the payment to us of any royalty thereon.

5 This invention relates in general to projectiles and more particularly has reference to an apparatus for, and a method of, stabilizing the flight of liquid containing shells.

10 The present invention as will be later understood, is directed primarily to stabilizing the flight of liquid filled projectiles fired from rifled muzzle loading mortars. It will be further apparent, however, that the invention is adaptable to all types of liquid containing shells.

15 It is well known that the true flight of projectiles fired from various types of rifled ordnance pieces, results from the rotating motion imparted to the same by the engagement of a band fixed thereon, with the rifling in the barrel of the piece from which the shell is fired. In obtaining the true flight of a stable projectile by rotation of the same, greater accuracy and an increased range is 20 achieved so that the advantage of stabilizing rotating liquid filled projectiles which have heretofore generally tumbled in flight will be manifest.

25 The relation of the weights of the projectile and the contained liquid is the principal factor as regards the stability of a rotating liquid filled shell flight. If the walls of the projectile are thick so that the weight of the contained liquid is negligible, and the liquid 30 is centered on the longitudinal axis of the shell, it is manifest that a liquid filling under these conditions will not greatly affect the flight of such a projectile.

35 In the instance where a thin wall projectile is filled with a liquid, however, it would be appreciated that the inertia of the liquid 40 on firing will initially set up a counter rotation of the liquid in the projectile and subsequently the frictional action of the contained liquid on the inner walls of the shell

will tend to dampen the motion of the same so as to brake the rotational velocity of the shell, and cause tumbling or wobbling.

45 An object of this invention is to provide a rotating liquid containing projectile in which the rotational velocity imparted to the contained liquid is the same as that given to the projectile on firing.

50 Another object of this invention is to provide a rotating liquid containing projectile which is stable in flight by reason of a provision for rotating the contained liquid with the projectile.

55 A further object of this invention is to provide a rotating liquid containing projectile with which true flight and maximum range may be obtained.

60 With these and other objects in view which may be incident to our improvements, the invention consists in the parts and combinations to be hereinafter set forth and claimed, 65 with the understanding that the several elements comprising our invention, may be varied in construction, proportions and arrangement, without departing from the spirit and scope of the appended claims.

65 In order to make our invention more clearly understood, we have shown in the accompanying drawings, means for carrying the same into practical effect, without limiting the improvements in their useful applications to the particular constructions, which for the purpose of explanation, have been made the subject of illustration.

70 In the drawings forming a part of this specification:

75 Figure 1 is a top view of a liquid containing projectile showing a plurality of vanes mounted therein for rotating the contained liquid with the projectile.

80 Figure 2 is a fragmentary sectional view of a projectile equipped with the vanes shown in Figure 1.

85 Figure 3 is a top view of another form of vane arrangement.

Figure 4 is fragmentary sectional view of a liquid containing projectile having the baffle or van arrangement shown in Figure 3, mounted therein.

5 Figure 5 is a fragmentary sectional view of the top of a liquid containing projectile showing still another form of baffle or vane mounted therein.

10 Figure 6 is a sectional view of the projectile shown in Figure 5 showing the baffle mounted therein, in elevation.

15 We have discovered that the flight of projectiles having a high percentage of the weight in the form of liquid or semi-liquid, may be stabilized, by mounting suitable baffles or partitions therein, so as to cause the contained liquid to rotate with the projectile. It will thus be appreciated that thin wall projectiles adapted to be filled with 20 liquids or low melting solids which become liquid or semi-liquid, may be stabilized in flight as well as the thick wall shells previously employed in which the weight of the contained liquid is small compared to the 25 weight of the shell.

In providing baffles or vanes in a liquid casing within a projectile, it will be appreciated that rotation of the shell will impart a similar rotational velocity to the contained 30 liquid so that the inertia of the liquid will become a minor quantity and there will be no appreciable friction between the liquid and the projectile in flight which will tend to dampen or retard the rotation of the shell.

35 It will of course be apparent that the exact construction of the baffles will vary according to the particular type of shell which it is desired to stabilize. It may generally be borne in mind that short lengths of partitions 40 or vanes may be suitable for projectiles in which there is a moderate weight of liquid as compared to the weight of the metal composing the projectile. In other shells, however, such as the type which is deemed the 45 most efficient for use in connection with muzzle loading rifle mortars where the weight of the metal is small as regards the weight of the contained liquid, it may be necessary to extend the vanes or the baffles 50 the full length of the projectile.

In connection with this invention, it will be appreciated that projectiles of various types for containing liquid may have the walls composed of much thinner and lighter 55 metal, so that the quantity of contained liquid may be greater than was ever heretofore contemplated. With suitable baffles or vanes mounted therein, the shell may be stabilized for true flight and long range, although the liquid filling constitutes practically the total weight of the loaded shell.

Referring more particularly to the accompanying drawings, there is shown in Figure 1 60 a shell having a form of vane arrangement mounted therein, in which a plurality of

longitudinal baffles or partitions are secured on the liquid casing thereof and attached to the projectile body so as to rotate the liquid filling the shell. The device shown in Figures 1 and 2 consists essentially of a plurality of rectangular plates 2 having the longitudinal inner edges connected to a central tubular member 3. The tube 3 is centrally attached to a cup 4 seated in the bottom 70 of the liquid casing and shaped to conform with the contour thereof.

The baffle plates 2 are secured in position by a plurality of circular bands 5 fitting in notches provided in the outer edges of the vane so as to present a flush surface therewith. The bands are preferably attached to the plates at the ends opposite the cup and at the center as shown. The baffle unit may be fixed in the liquid casing of a projectile by spot welding the circular band 5 85 and cup 4, although it will be apparent that the same may be fixed in any other desirable manner.

The mobile nature of the liquid filling makes it desirable to allow communication 90 between the different compartments formed in the casing by the baffle unit. For this purpose, a plurality of apertures 6 are provided in each of the vanes.

It will be appreciated that if the compartments were all liquid tight and each compartment loaded to the same degree, it would not be necessary to have inter-communication therebetween. As such exact loading is not usually obtained in economical shall production and filling, however, it is deemed desirable to provide apertures 6 or other means of communication so that the height of the liquid in the several compartments may be self-adjusting.

It will be apparent that in a liquid containing projectile having the baffle unit described therein, the liquid filling in the several compartments of the projectile will rotate with the projectile and counter-movement between the liquid and projectile which might act to detrimentally affect the rotation of the projectile and cause it to become unstable in flight, will be eliminated.

As hereinbefore described, it will be apparent that the length or number of partitions or vanes in the manner of mounting may be varied to suit the particular type of shell in which it is desired to install the same, according to the thickness thereof, and the 115 relative weight of metal composing the projectile body and the contained liquid.

Another type of baffle arrangement is shown in Figures 3 and 4 in which three rectangular plates 7 are connected by strips 8 120 flanged as at 9. The strips 8 are arranged to form a triangle in cross-section, the flanges being juxtaposed and the outer edges of the plate 7 being interposed therebetween so as to form three radial partitions making an 130

angle of 120° to each other with a central longitudinal opening between the inner edges thereof, as distinguished from the plates 2 shown in Figure 1, which make an angle of 5 90° to each other and terminating adjacent a central tubular member.

In Figures 5 and 6, there is shown still another form of baffle arrangement in which a pair of plates 11 are formed with central 10 longitudinal semi-cylindrical grooves 12 and side flanges 13 are juxtaposed so as to divide the liquid casing of the shell into two compartments semi-cylindrical in cross-section. The respective plates are spot welded together so as to form a single piece. The top 15 of the baffle is cut away as at 14 to provide for receiving the closing head of the shell and at the bottom is provided with a notch 15 as shown in Figure 6, so as to allow for 20 maintaining the liquid level in both compartments.

The baffle formed by the plates 11 is adjacently provided with a series of staggered apertures 16 and 17. In this manner, while 25 liquid contained in the projectile may flow from one compartment to the other, the same will nevertheless be caused to rotate the shell in flight. It will be manifest from the foregoing that the length, shape and position of 30 the baffles within a liquid carrying projectile may be varied according to the particular requirements which it is sought to obtain.

There is accomplished by this invention, a baffle arrangement for mounting in liquid 35 containing projectiles whereby the contained liquid is caused to rotate with the projectile in flight, without counter-movement therebetween. This results in stabilizing liquid containing projectiles in flight and obtaining 40 greater range, without tumbling caused by the retarding action of a liquid in frictional contact with the fluid casing by reason of the inertia of the liquid.

While we have shown and described the 45 preferred embodiment of our invention, we wish it to be understood that we do not confine ourselves to the precise details of construction herein set forth, by way of illustration, as it is apparent that many changes 50 and variations may be made therein, by those skilled in the art, without departing from the spirit of the invention, or exceeding the scope of the appended claims.

We claim:

55 1. A rotary projectile comprising a fluid containing casing having a plurality of longitudinally extending apertured radial partitions mounted therein forming separate communicating compartments.

60 2. A rotary projectile comprising a fluid containing casing having a plurality of fixed longitudinally centrally connected radially extending partitions with apertures therein.

65 3. A rotary projectile comprising a fluid containing casing having a central tubular

member provided with fixed radially extending apertured baffles.

4. A rotary projectile comprising a fluid containing casing having a pair of juxtaposed apertured members formed to provide 70 a central longitudinally extending tubular member, a pair of fixed oppositely disposed radially extending partitions with staggered apertures therein.

5. A rotary projectile comprising a fluid 75 containing casing having a central tubular member provided with a plurality of fixed radially extending apertured partitions secured in position by a plurality of bands.

6. A rotary projectile comprising a fluid 80 containing casing having a hollow longitudinally extending central member provided with fixed interior and exterior baffles.

7. A rotary projectile comprising a fluid 85 containing casing having three longitudinal flanged members, the flanges juxtaposed forming a central member triangular in cross-section and three longitudinal radially extending plates having the outer edges interposed between the juxtaposed flanges, the 90 inner edges of the plates forming baffles inside the central member and the juxtaposed flanges and the outer edges of the interposed plates forming baffles outside the central member. 95

In testimony whereof we affix our signatures.

LEWIS M. McBRIDE.
